Inventor:

William G. Houk.

UNITED STATES PATENT OFFICE.

WILBUR G. HOUK, OF CRAWFORDSVILLE, INDIANA.

WAGON-BOX SHIELD.

SPECIFICATION forming part of Letters Patent No. 670,990, dated April 2, 1901.

Application filed March 24, 1900. Serial No. 10,114. (No model.)

To all whom it may concern:

Be it known that I, WILBUR G. HOUK, a citizen of the United States, residing at Crawfordsville, in the county of Montgomery and State of Indiana, have invented a new and useful Improvement in Wagon-Box Shields, of which the following is a specification.

My invention relates particularly to a metallic shield for protecting and strengthening 10 that portion of the wagon-box overlying the vehicle-bolster adjacent the bolster-standard, and has for its object the production of a device for receiving the bolster and for shielding the wagon-box adjacent thereto; and to 15 this end my invention consists in the peculiar construction, combination, and arrangement of the several parts, as will be fully pointed out in the following description and claims.

Referring to the accompanying drawings, 20 forming a part of this application, in which like letters of reference indicate corresponding parts throughout the several views, Figure 1 is an elevation of a part of a wagon-box overlying the bolster adjacent the standard and of my invention entire secured thereon.. 25 Fig. 2 is a perspective view. Fig. 3 is a bottom plan of the same. Fig. 4 is a detail view showing the reinforcement part. Fig. 5 is an end elevation showing the reinforcement part 30 of my invention.

A refers to a detached part of an ordinary wagon-box, B to the wagon-bolster, and C to the bolster-standard.

My invention, by preference constructed of 35 integral sheet-steel, comprises a body part D, an upstanding wing E, a pair of downstanding jaws F, a pair of lateral flanges G, a pair of triangular-shaped braces H between the jaws and the flanges, and the reinforcing parts I². 40 The vertical wing E is bent up from the outer end of the body part and is provided near its outer corners with suitable openings for the reception of the through-bolts I, which rigidly secure it to the side of the wagon-box A. The 45 jaws F, bent downward from the sides of the body part, receive the wagon-bolster B between them for holding the wagon-box stationary thereon. The lateral flanges G are for the purpose of providing a fastening to 50 the bottom of the wagon-box away from the bolster and for giving my device such ample base that it can be fastened securely to the

bottom of the wagon-box by means of the openings G' for the reception of ordinary through-bolts. The triangular-shaped braces 55 H form a substantial brace between the walls of the jaws F and the flanges G, which prevents the walls of the jaws F giving or bending laterally. The reinforcing parts I², bent inward and downward to the bottom of the 60 jaws F and across the body part D, are provided for the purpose of reinforcing the jaws F, which imparts by the gravitation or weight of the wagon-box greater strength and firmness to my device. 65

My invention is rigidly secured on the wagon-box over the wagon-bolster adjacent the bolster-standard for shielding and strengthening that portion of the wagon-box immediately overlying the wagon-bolster adjacent 70 the bolster-standard and for holding the wagon-box stationary on the wagon-bolster, which prevents any sliding thereon.

In the construction of my device cast, wrought, or malleable iron or similar hard 75 material suitable for its purpose may be used and modifications in structure and form may be made without departing from the spirit and scope of my invention.

In the above construction I produce a simple, durable, and efficient device for shielding, strengthening, and holding the wagon-box of vehicles more effectually than has been done heretofore. 80

Having thus fully described my invention 85 and set forth the use and advantages thereof, what I claim as new, and desire to secure by Letters Patent, is—

1. A wagon-box shield comprising a body part, an upstanding wing, a pair of downstanding jaws, a pair of lateral flanges, a pair of triangular-shaped braces between the walls of the jaws and the flanges and means for rigidly securing the same to the wagon-box, all made in the manner and for the purposes set 90 forth, substantially as specified. 95

2. In combination with a wagon-box, an integral shield mounted thereon over the bolster adjacent the standards, the same comprising a body part, an upstanding wing, a pair of downstanding jaws, a pair of lateral flanges, a pair of triangular-shaped braces between the walls of the jaws and the flanges and suitable openings and means for rigidly 100

securing the upstanding wing and lateral flanges to the wagon-box, all as and for the purpose set forth, substantially as specified.

3. In a wagon-box shield having a body part provided with an upstanding wing, a pair of downstanding jaws, a pair of lateral flanges, a pair of triangular-shaped braces between the walls of the jaws and the flanges, a pair

of reinforcing parts for the jaws and the body part and means for rigidly securing the same to the wagon-box.
